UNITED STATES PATENT OFFICE.

HENRI FABRICE MÉLOT, OF PARIS, FRANCE.

PROPELLING EJECTOR.

Application filed December 10, 1923. Serial No. 679,785.

To all whom it may concern:

Be it known that I, HENRI FABRICE MÉLOT, a citizen of the Republic of France, residing at Paris, France, 43 Avenue du Maine, have invented certain new and useful Improvements in Propelling Ejectors, of which the following is a specification.

This invention relates to a propelling device of the kind described in Letters-Patent of the United States No. 1,375,601 in which a motive fluid sent through a plurality of ejector tubes in series draws atmospheric air and causes between the front and rear ends of the ejector tubes a difference of pressure producing a thrust on the tubes, so that when the latter are mounted on a terrestrial vehicle, a marine vessel or an aircraft the thrust causes propulsion thereof. In accordance with the present invention, in order to improve the efficiency of such devices, the first ejector tubes of the series are of greater length than the following ejector tubes so as to provide a sufficient distance 25 way for the high speed mixture of motive fluid and air aspired to have proper time to expand and carry along the maximum amount of air.

The accompanying drawing shows diagrammatically an axial section of an embodiment of the invention.

The injection nozzle *a* receives motive fluid from any generating device such for as example that described in my application Serial No. 679,784, filed even date. Said device is designated on the drawing by the letter *A* and is not claimed herein. Nozzle *a* opens into the first ejector tube *b* which is open to the atmosphere at *c*. Each following ejector tube *b*, *b*₂ is of lesser length than the preceding tube or of equal length.

The air drawn in at *c* mixes with the motive fluid injected through the nozzle *a* and the mixture whose initial speed is very high is able to apply itself against the inner walls of the ejector tube *b* and has time to expand properly owing to the great length of said tube. When the fluid reaches the second ejector tube *b*, its speed is slower and it is not necessary to have it follow such a great axial distance as in the

first tube for it to have the requisite expansion and produce the maximum reaction on the surrounding atmospheric air. The same effect occurs with the following ejector tubes.

It may happen that the passage areas in the last ejector tubes becomes too great with respect to their length. In such case, according to the invention, a needle *d* having a suitable profile is placed inside the ejector tubes and the nozzle if required, so as give them the proper passage areas. Said needle may be made movable in the axial direction so as to permit of regulating the areas.

The invention may also be applied to ejector tubes in series supplying gas turbines or securing the blast of metallurgical apparatus.

What I claim is:

1. A propelling device with Venturi ejector tubes in overlapping series wherein the first tubes have a greater length than the following tubes and each tube has its outlet arranged at the restricted portion of the following tube, whereby sufficient distance of passage is provided for the expansion of the mixture of motive fluid and air aspired.

2. A propelling device with ejector tubes in series wherein the first tubes are of greater length than the following tubes, and having a needle in the opening of said tubes for providing the proper free passage areas.

3. A propelling device with ejector tubes in series the first tubes having a greater length than the following, each tube having a convergent part and a divergent part, the corresponding parts of all the tubes being parallel.

4. A propelling device with ejector tubes in series the first tubes having a greater length than the following, each tube having a convergent part and a divergent part, the corresponding parts of all the tubes being parallel, and each tube having a streamlined surface.

In testimony whereof I have signed my name to this specification.

HENRI FABRICE MÉLOT.
